his ATTORNEY.

UNITED STATES PATENT OFFICE.

WILLIAM KUEHNLE, OF WOODHAVEN, NEW YORK.

SAFETY GUARD.

1,407,203.

Specification of Letters Patent. Patented Feb. 21, 1922.

Application filed April 12, 1919. Serial No. 289,631.

To all whom it may concern:

Be it known that I, WILLIAM KUEHNLE, a citizen of the United States, residing in Woodhaven, in the county of Queens and 5 State of New York, have invented certain new and useful Improvements in Safety Guards, of which the following is a specification.

This invention relates to printing presses 10 in general and more especially to safety guards for printing presses.

Among the main objects of the present invention, it is aimed to provide a safety guard attachment that can be conveniently 15 secured in place without any reconstruction of the presses, and which can be quickly and readily adjusted to suit any requirements.

These and other features, capabilities and 20 advantages of the invention will appear from the subjoined detail description of certain specific embodiments thereof illustrated in the accompanying drawings in which

Figure 1 shows a printing press diagrammatically and equipped with one form of 25 safety guard shown in end elevation.

Fig. 2 is a fragmental side elevation of the embodiment shown in Fig. 1, and in protecting position.

Fig. 3 is an end elevation of the same in 30 retracted position.

Fig. 4 is an end elevation of another form shown in extended or protecting position.

In the embodiment shown in Figs. 1, 2 and 3, there are secured to the sides of 35 the ordinary printing press platen 5, the brackets 6 having portions 7 secured to the edges of the platen so that the sides thereof substantially aline with the face 8 of the platen. Parallel to and spaced from the 40 face 8 of the platen, the portions 9 extend from the portions 7. The portions 9 each have pairs of widely spaced apart guides 10 and 11 extending inwardly from the portions 9 to receive the slidebars 12. To the

45 upper ends of the slidebars 12 is secured the rod 13 to which a curtain 14 is secured, the other end of which curtain is preferably secured to a rod 15 secured to the guides 11 formed on the brackets 6.

50 The lower ends of the slidebars 12 have projections 16 extending rearwardly of the face 8 of the platen. The projections 16 are connected by the links 17 to any suitable anchoring means, in the present instance,

the projections 18 formed on the housing 55 in which the shaft of the platen 5 is journaled. The links 17 are provided with a plurality of openings 19 to receive suitable fastening means such as the screws 20 whereby the extent the curtain is projected may 60 be adjusted and whereby in addition the adjustment of the guard to different sizes of presses is facilitated. As shown, the ends of the links 17 are preferably secured to the projections 16 by means of screws or 65 rivets 21.

From the foregoing it will be seen, as shown in Fig. 2, when the platen is withdrawn out of printing position, the links 17 will positively draw the slidebars 12 down 70 so that the curtain is withdrawn out of guarding position. On the other hand, when the platen is rocked over into printing position as shown in Fig. 1, the links 17 will positively actuate the slidebars 12 so as to 75 project the curtain into guarding position.

In the embodiment illustrated in Fig. 4, brackets 6' and slidebars 12' similar to the brackets 6 and slidebars 12 of the embodiment illustrated in Fig. 1 are provided. 80 Here instead of the rigid links 17, flexible connecting means such as the chains 22 are provided which connect the projections 16' with the projections 18'. The chains 22 are preferably sufficiently long to suit extreme 85 cases, and thus when shorter distances are formed between the connecting points, the projections 18' and 16', it is only necessary to drive the fastening means 20' through the chains 22 at distances removed from the 90 ends thereof as illustrated.

When the chains 22 are used, it is preferable to provide the springs 23 which are strained between the abutments 24 formed on the upper ends of the slidebars 12' and 95 the abutments 25 formed on the guides 11' on the brackets 6'.

With the modification shown in Fig. 4, when the platen is rocked over into printing position as shown, the chains 22 will positively actuate the slidebars 12' to project the curtain into guarding position. On the other hand, when the platen is rocked out of printing position, the chains 22 will become slack and the slidebars 12' will drop down out of guarding position, the springs 23 being provided to insure this action.

It is obvious that various changes and

modifications may be made to the details of construction without departing from the general spirit of the invention.

I claim:

- 5 1. The combination with the platen of a printing press, of a pivot housing stationary relative to said platen, a pivot member for said platen journaled in said pivot housing, a safety guard comprising brackets secured 10 to the edges of the platen adjacent to the face thereof, guides formed thereon, slidebars slidably mounted in said guides, a curtain suspended between said slidebars and said brackets, abutment means on said pivot housing above the axis of rotation of the platen, said platen rocking away from said 15 abutment means when swinging into printing position, and links adjustable as to

length connecting the lower ends of said slidebars with said abutment means so as to 20 project said safety guard when the platen is rocked into printing position.

2. The combination with a printing press having a platen pivotally mounted relative to a housing, of a safety guard comprising 25 brackets secured to the edges of the platen adjacent to the face thereof, guides formed thereon, slidebars slidably mounted in said guides, a curtain suspended between said slidebars and said brackets, and a pair of 30 links connecting the lower ends of the slidebars to said housing, the links having a plurality of openings with which the fastening means co-operate to facilitate adjustment of the guard.

WILLIAM KUEHNLE.
